W. F. BOSSERT.
 ELECTRIC SWITCHBOARD.
 APPLICATION FILED JULY 17, 1903.

NO MODEL.

UNITED STATES PATENT OFFICE.

WILLIAM F. BOSSERT, OF UTICA, NEW YORK, ASSIGNOR TO THE BOSSERT ELECTRIC CONSTRUCTION COMPANY, OF UTICA, NEW YORK.

ELECTRIC SWITCHBOARD.

SPECIFICATION forming part of Letters Patent No. 738,519, dated September 8, 1903.

Application filed July 17, 1903. Serial No. 165,901. (No model.)

To all whom it may concern:

Be it known that I, WILLIAM F. BOSSERT, residing at Utica, in the county of Oneida and State of New York, have invented certain improvements in Electric Switchboards, of which the following is a specification.

The present invention relates to improvements in a panel or switchboard adapted for use in connection with fuse-wires and fuse-plugs.

The especial feature of the invention consists of improvements in the construction of the connecting parts of the branch-circuit cross-connecting bars, whereby the common screw-threaded fuse-plug can be employed to close the circuit and form a perfect electrical contact and avoid introducing resistance at that point.

In the drawings which illustrate the invention, Figure 1 is a plan view of a panel or switchboard with the fuse-plugs removed. Fig. 2 is a side elevation of the same. Fig. 3 is a section on line xx of Fig. 1, showing the fuse-plug in its seat and in section. Figs. 4 and 5 are respectively a plan and an end elevation of a modification of the invention with the fuse-plug removed.

A represents a panel constructed of any suitable insulating material, and B B² are the common circuit-terminals adapted for the reception of leads and are secured to the panel by screws 1 1 and the binding-screws 2 2.

C and C² are common circuit-terminal conductors having feet t, which are secured to the panel by the screws 3 3, which also serve as binding-screws to connect the fuse-wires s s with the binding-screws 2 2, and E, E², E³, and E⁴ are conductors or terminal branch-circuit cross connections, which are secured to the terminals C C² in a common and usual manner by the screws 4 and 5. The terminals E extend to each side or edge of the panel and at their extremities are adapted to be connected to the branch leads, as will now be explained.

D is an arch-shaped member, shown as provided with the feet a and r and the arch central portion b, ring-shaped in plan, having an internally-screw-threaded nut c. The foot a is secured to the panel by the bolt z, and the foot r is similarly fastened to the panel by a bolt y, which passes through the foot and the

terminal E, separated from the foot r by the insulation w, there being around the bolt a ring of insulation u, separating it from the 55 said terminal.

In the modification shown in Figs. 4 and 5 the foot r is broadened on its sides, as represented by m, and is provided with ears n n on each side, which are secured to the panel 60 by the screw-bolts o o. The portion m forms an arch over the extension E and leaves an air-space p all around the same, which space is preferably filled with insulation.

F is the fuse-plug, made with a hollow plug 65 of insulation, usually porcelain, and having upon its lower exterior portion a threaded sleeve-contact h. Its upper portion is of larger diameter and has a metal cap f secured to it. A fuse-wire is soldered to the inner surface of the metal piece h at the point 10 and curves inward and downward through the bottom of the plug to a central end contact upon its exterior in a common manner. The screw-thread h of the plug is screwed into 75 the nut c of the member D, with which it makes electrical contact, until the said end contact bears upon the end of the terminal E, with which it makes electrical contact, and a circuit is established from the branch lead 80 binding-screw v to the terminal E. The fuse-plug receiver D being supported on its sides by a plurality of feet more than two can be provided, if necessary, central of which is the screw-socket c. It constitutes a stiff and rigid 85 arch which resists the screw-thrust of the plug, and consequently the latter may be screwed hard down onto the end of the terminal E and a perfect electrical contact made.

I claim as my invention—

1. The combination with a fuse-plug having a threaded sleeve-contact and a central end contact, of a panel or switchboard provided with circuit-terminals, an arch-shaped member connected with said sleeve-contact and 95 insulated from the circuit-terminals, ring-shaped in plan and internally screw-threaded and having a plurality of feet, one of which is connected to the branch lead, the said end contact being connected to a circuit-terminal, 100 as set forth.

2. The combination in a panel or switchboard, a base of insulating material, common circuit-terminal conductors, and terminal

- branch-circuit cross connections, the latter provided with plug-fuses with a support for each plug consisting of an arch-shaped member insulated from and inclosing its cross-
5 connection terminal, ring-shaped in plan and internally screw-threaded and having a plurality of feet, one of which is connected to the branch lead, as set forth.
3. The combination with a fuse-plug having a threaded sleeve-contact and a central end contact, of a panel or switchboard provided with circuit-terminals, an arch-shaped member connected with said sleeve-contact and insulated from and inclosing the circuit-
10 terminal ring-shaped in plan and internally screw-threaded, and having a plurality of feet, one of which is connected to the branch lead, the said end contact being connected to a circuit-terminal, as set forth.
- 15 4. The combination with a fuse-plug having a threaded sleeve-contact and a central end contact, of a panel or switchboard provided with circuit-terminals, an arch-shaped member connected with said sleeve-contact and insulated from and inclosing the circuit-
20
- 25

terminal, ring-shaped in plan, and internally screw-threaded, and having feet upon opposite sides in line with the circuit-terminal, one of which is connected to the branch lead, the said end contact being connected to a circuit-terminal, as set forth. 30

5. The combination in a panel or switchboard, a base of insulating material, common circuit-terminal conductors, and terminal branch-circuit cross connections, the latter provided with plug-fuses with a support for each plug consisting of an arch-shaped member insulated from its cross connection, ring-shaped in plan and internally screw-threaded, and having a plurality of feet, one of which 35 40 is connected to the branch lead, as set forth.

In testimony whereof I have signed my name to this specification, in the presence of two subscribing witnesses, this 15th day of July, 1903.

WILLIAM F. BOSSERT.
